PUSH BUTTON OPERATING MECHANISM
FOR PERMEABILITY TUNING PURPOSESMartin J. Kirk, Chicago, Ill., assignor to Johnson
Laboratories, Inc., Chicago, Ill., a corporation
of Illinois

Application February 20, 1939, Serial No. 257,313

21 Claims. (Cl. 171—242)

My invention relates to operating devices for inductors having variable inductance by relative movement of the coils and ferromagnetic cores of said inductors, the inductance variation being thus effected by changing the permeability of the magnetic paths of the inductors, which, where said inductors are used as parts of resonant circuits, is an effective means for tuning said resonant circuits over a desired range of frequencies, for example over the broadcast band. My invention relates particularly to mechanism of the kind referred to, in which a plurality of push-button mechanisms capable of reciprocating movement may be selectively operated to establish different conditions of inductance, or tuning to a desired frequency by said selection, as the case may be, in combination with a plurality of inductors having variable inductance and operated by the push-button mechanism to secure the desired inductances or to tune the several resonant circuits to a selected frequency, as the case may be.

With operating mechanism of the push-button type, it is desirable that the key bars shall not be required to have excessive movement, that is to say, the finger of the operator should move only a limited distance for convenience and comfort in operating the mechanism, say for example $\frac{1}{2}$ " to $\frac{3}{4}$ ", and yet at the same time the inductors which are conveniently varied as to their inductance by movement of their ferromagnetic cores, are provided with operating mechanism which generally is required to move through much greater distances, since the coils of the inductors are preferably of relatively small diameter and large length, and the cores employed therewith are of corresponding proportions for example the cores may be from $1\frac{1}{4}$ " to $2\frac{1}{2}$ " long. This indicates the need for motion-multiplying mechanism of some kind between the push-button mechanism and the operating devices directly associated with the cores. Again, on account of it being desirable to have the movement of the push-button mechanism of a reciprocating nature, for example by means of longitudinally movable key-bars, I find it advisable to mount the reciprocable push-button mechanism on one side of a mounting plate and to mount the inductors with their longitudinally movable cores on the other side of said mounting plate, to the end that the complete mechanism may occupy as small bulk as possible. To accomplish this, I provide by my invention rotary mechanism connecting the push-button mechanism with the cores of the inductors, which rotary mechanism ex-

10 tends through the mounting plate, and is provided with motion multiplying devices, so that limited movement of a selected push-button, which is in the direction of the selected key-bar, is transformed from straight line motion into rotary motion; said motion is then multiplied and the multiplied motion is again transformed into straight line motion to operate the cores of the inductors.

15 By my invention I also provide improved means by which any one of the push-button devices may be adjusted as desired, to secure any amount of operation of the cores of the inductors, within the range of movement of said cores, and in this way any desired inductance values may be selected by said push-button devices, or any particular frequencies may be tuned selectively by said push-button devices where the inductors are parts of resonant circuits, as the case may be.

20 My invention will be best understood by referring to the accompanying drawings illustrating a preferred embodiment thereof, in which:

Fig. 12 is a vertical, sectional view to an enlarged scale through the key-bar shown in Fig. 11, taken along the line 12—12 in Fig. 11;

Fig. 13 is a side elevation of a part of the key-bar structure shown in Fig. 12;

Fig. 14 is a horizontal, sectional view of a part of the structure shown in Fig. 10, taken along the line 14—14 in Fig. 10;

Fig. 15 is a plan view to an enlarged scale of a modified form of sector for use with the construction of the operating mechanism illustrated in Figs. 1 and 2; and

Fig. 16 is a side elevation of the sector construction shown in Fig. 15.

Similar numerals refer to similar parts throughout the several views.

As shown in Fig. 1, my invention consists of a mounting plate 10 supporting upper and lower horizontal plates 11 and 12 which are slotted as illustrated in Figs. 3 and 5, to form guides for key-bars 13 and to maintain said key-bars in vertical position, for the position of the mechanism as a whole which is illustrated in Figs. 1 and 2. Each of the key-bars 13 carries just below the plate 11 a sector 14 of sheet metal pivotally connected with the key-bar at 15, which sector carries two lugs 14a and 14b extending in opposite directions from the sector, the lugs 14a, as shown in Fig. 1, extending towards the observer and the lugs 14b extending away from the observer. Each of the key-bars 13 carries a key-rod 16 extending above the corresponding key-bar and having rigidly secured to its upper end a finger button or knob 17. The rod 16 is supported for rotary movement by a flange member 18 formed from the key-bar 13, and at its lower end the rod is threaded, as more clearly shown in Fig. 6, to engage the horizontal leg of an angle member 19 extending through the key-bar 13 and so positioned that its vertical leg lies against the outer vertical surface of the sector 14, as a result of which, when the rod 16 is turned by the button 17 to slightly raise the horizontal leg of the angle member 19, the vertical leg of said angle member presses tightly against the flat surface of the sector 14 and thereby presses the sector tightly against the key-bar to clamp the sector in any position to which it may be adjusted, without producing a binding action between the angle member 19 and the threads on the rod 16. As shown in Figs. 6 and 7, the pivotal connection 15 of the sector 14 also secures to the sector and key-bar a perforated clip 20 to receive one end of a key-bar returning spring 21, as shown in Fig. 2, the other end of said spring engaging the top horizontal plate 11.

Each of the key-bars 13 is constructed as above described.

The horizontal plates 11 and 12 are held in place by side plates 22 and 23 secured to the mounting plate 10, and said side plates also support in vertical position a bearing plate 24 extending horizontally across the front lower portion of the device to support shafts 25 and 26 in horizontal position, the shaft 25 extending through the mounting plate 10 for a purpose below described and the shaft 26 having its ends substantially flush with the outer surfaces of the mounting plate 10 and the bearing plate 24.

As illustrated in Fig. 1, the shaft 25 has rigidly secured thereto a bell crank member 27 having arms 27a and 27b extending in diametrically opposite directions from the shaft and in different planes as illustrated in Fig. 5, said bell crank member having a third crank arm 27c extending from the shaft 25 at substantially right angles to the arms 27a and 27b and in substantially the

plane of the arm 27a. The shaft 26 carries a bell crank member 28 having arms 28a, 28b and 28c of the same construction as the construction and disposition as the arms 27a, 27b and 27c respectively. The outer ends of the arms 27a and 28a are pivotally connected with vertical members 29a extending downwardly from a transverse bar 29 disposed adjacent the key-bars 13 below the sectors 14, so that the upper edge of said transverse bar 29 is below and in line with the lugs 14a on the sectors 14, as illustrated in Fig. 4. The bell crank arms 27b and 28b are pivotally connected with a second transverse bar 30 of the same construction as the bar 29, which bar 30 is disposed adjacent the opposite sides of the key-bars 13 and below the sectors 14, so that its upper edge is below and in line with the lugs 14b on the sectors 14. The arms 27c and 28c of the bell crank members 27 and 28 are pivotally connected by a third transverse bar 31. The arms of the bell crank levers 27 and 28 are all of the same effective length, and the shafts 25 and 26 are spaced a substantial distance apart, as a result of which the bars 29, 30 and 31 are maintained in parallel relation with each other at all times, and any rotary movement imparted to either of the shafts 25 and 26 is effectively communicated to the other shaft to rotate it substantially the same amount. It will further be observed that on account of the relation of the arms 27a and 27b to each other, and the similar relationship of the arms 28a and 28b, any movement imparted to one of the bars 29 or 30 by rotary movement of either of the shafts 25 and 26 will be accompanied by similar and opposite movement of the other of said bars, that is to say, if for any reason the bar 28 is moved downwardly, the bar 30 is at the same time moved upwardly, and if at the beginning of operation of either of the shafts 25 and 26 the bar 30 happens to be uppermost and the bar 30 is then moved downwardly, the bar 29 is moved upwardly.

The bars 29 and 30 are so disposed relatively to the sectors 14 that when any one of the key-bars 13 is depressed, one of the lugs 14a and 14b on the sector of the selected key-bar will engage one of the transverse bars 29 and 30, depending on which of said bars is uppermost, and that continued downward movement of the selected key-bar will depress the uppermost transverse bar 29 or 30 and move it downwardly until the other one of the lugs 14a or 14b on the selected sector 14 engages the other of the transverse bars 29 and 30, which limits further downward movement of the selected key-bar. Thus in any case one of the transverse bars 29 and 30 operates as an operating bar and the other of said bars operates as a stop bar when any one of the key-bars is operated. It will be observed that the angular position of the sector 14 on any one of the key-bars 13, determines the maximum amount of transverse movement that may be imparted to the bars 29 and 30 by the lugs 14a and 14b on said sector, that is to say, when said lugs are in nearly horizontal alignment the amount of transverse movement imparted to said bars 29 and 30 is relatively small, and when said sector is adjusted angularly so that one of the lugs 14a and 14b is in its uppermost position, the amount of possible movement imparted to the bars 29 and 30 by said lugs is a maximum. In this way, by adjustment of any sector 14 on its key-bar 13, the amount of rotary movement imparted to the shafts 25 and 26 by depression of the corresponding key-bar, may be adjusted

as desired. It will also be observed that regardless of the position of the transverse bars 29 and 30 at the beginning of their operation by a selected one of the sectors 14, when the selected key-bar is depressed until it will go no further, the transverse bars 29 and 30 will occupy a definite relation to each other vertically, that is to say, any particular adjustment of a selected one of the sectors 14 on its key-bar will have the effect for operation of the corresponding key-bar, of always moving the transverse bars 29 and 30 to the same position, and therefore moving the shafts 25 and 26 to the same angular position, as long as the angular position of the sector on the selected key-bar is maintained. It will also be observed that by releasing the sector on any key-bar by turning the key-rod 16, the corresponding sector may be moved angularly on its key-bar to effect any desired position vertically of the transverse bars 29 and 30 and any desired angular position of the shafts 25 and 26, within the range of the mechanism.

As shown in Figs. 2 and 4, insulating tubes 32 are supported in horizontal position substantially parallel with the mounting plate 10 by an end flange 10a formed on the mounting plate and by a plate 33 of insulating material supported in vertical position by said mounting plate. The tubes 32 carry inductance coils 34 and contain with a sliding fit ferromagnetic cores 35, the ends of which cores have secured to them slender rods 36 threaded at their outer ends to engage thin-walled insulating sleeves 37 held firmly in engagement with a vertically extending yoke 38 by resilient clips 39 which, as more clearly shown in Fig. 9, are secured to the yoke 38 by any suitable means, for example rivets 40.

As shown in Fig. 2, the mid-portion of the yoke 38 is rigidly secured to one end of a horizontal bar 41 supported in sliding engagement with a flange member 42 formed from the mounting plate 10. The shaft 25, where it projects through the back face of the mounting plate 10, has rigidly secured thereto a crank 43 pivotally connected at 44 with the mid-portion of a lever 45, the lower end of which is pivotally connected at 46 with the mid-portion of the yoke 38. The upper end of the lever 45 is pivotally connected at 47 with one end of a link 48, the other end of which is pivotally connected at 49 with the mounting plate 10. The distance from the axis of the shaft 25 to the center of the pivotal connection 44 is equal to the center-to-center distance of the pivotal connections 44 and 46, and is also equal to the center-to-center distance of the pivotal connections 44 and 47, and the length of the link 48 and the position of its pivotal support 49 are so chosen as to place the pivotal connection 47 vertically over the axis of the shaft 25 and to place the link 48 in horizontal position, assuming that, as shown in Fig. 2, the cores 35 and the yoke 38 are to be moved horizontally. With the construction described the movement horizontally of the pivotal connection 46 is practically in a horizontal line through the axis of the shaft 25, the amount of departure from exact straight line movement being determined by the length of the link 48. To limit the slight error introduced by the use of the link 48, angular movement of the crank 43 and shaft 25 is limited to substantially 90° by stop lugs 50 and 51 formed from the mounting plate 10, said possible movement being substantially equally divided on either side of a vertical line through the axis of the

shaft 25. It will be noted that the limitation of angular movement of the shaft 25 is also advisable from the standpoint of transverse movement of the transverse bars 29 and 30, and to compensate for this limited movement the lever 45 serves to multiply the motion so that the yoke 38 is moved twice as far horizontally as is the pivotal connection 44 for angular movement of the shaft 25. A spring 52 engages the pivotal connections 47 and 48, to eliminate lost motion in said connections, and springs 53 and 53' respectively carried by the yoke 38 and the lever 45, engage the pivotal connections 46 and 44 to eliminate lost motion from those connections.

15 The insulating sleeves 37 are in threaded engagement with the slender rods 36 and the pressure of the resilient clips 39 is sufficient to hold said threaded rods against turning in said sleeves unless it is desired to adjust the cores 35 relatively to the coils or relatively to each other, which may readily be done by turning the threaded rods in the sleeves for aligning or tracking purposes.

As shown in Fig. 4 the upper portions of the 25 key-bars 13 and the sectors 14 carried thereby are located in inclined and overlapping positions as to said sectors, to reduce to a minimum the total width of the housing required to contain a given number of key-bars, and to at the same 30 time displace the lugs 14a and 14b carried by each sector in a direction from front to rear of the device, a sufficient amount to so space the transverse bars 29 and 30 from front to rear of the device that the lower portions of the key-bars may pass freely between them and still be disposed vertically below the said lugs respectively. The key-bars 13 just below sectors 14 are twisted slightly so that their lower portions are in substantially the same plane and substantially parallel with the mounting plate 10, as shown in Fig. 5. As illustrated in Fig. 5, the shaft 25 is extended through the bearing plate 24 to rigidly engage a finger knob 54 to facilitate turning the shaft 25 by hand when it is desired to manually adjust the cores 35.

45 In using the device described, to tune resonant circuits of which the coils 34 may be parts, for example in radio receivers constructed to cover a given range of frequencies, such as the broadcast band, the sectors 14 may be conveniently adjusted so that the corresponding key-bars will severally tune the resonant circuits to different frequencies and corresponding stations of said band in the following manner: Any desired station of said band may be carefully tuned by means of the finger knob 54, and then with the cores 35 in the position given them to effect said tuning, the rod 16 of the desired key-bar is turned to release the angular clamp 19, and the selected key-bar 13 is depressed until the transverse bars 29 and 30 engage the lugs 14a and 14b of the selected sector 14, which operation turns the sector on its pivotal support 15, and further downward movement of the selected key-bar is prevented by said transverse bars. The rod 16 is then turned to press the angular clamp 19 against the sector 14 and in that way to clamp the sector tightly against the key-bar, which holds the sector in its adjusted position and at the same time tightens the rod 16 against accidental turning. Thereafter, and unless the sector 14 is again adjusted, operation of the selected key-bar will always move the cores 35 to the required position to tune the resonant circuits containing the coils 34, to the frequency of the desired sta-

tion, regardless of the position of the transverse bars 29 and 30 at the beginning of the downward movement of the selected key-bar, and downward movement of the selected key-bar will be in every case limited and stopped by said transverse bars 29 and 30, when the cores 35 have been moved to their said tuning position. In the same manner, each of the other sectors may be similarly adjusted to a different station or frequency in the band of frequencies, and thus the several key-bars may be the means of selectively tuning the resonant circuits to different frequencies or different transmitting stations, as desired.

In Figs. 10-14, inclusive, I illustrate a modified form of my operating mechanism which differs from that above described, in that each of the key-bars when actuated to move the ferro-magnetic cores to a particular position relatively to the coils associated with said cores, is retained in its depressed position by suitable locking mechanism below described, against the action of a spring tending to move said cores to one of their extreme positions, which is their position of rest until and unless they are moved therefrom by one of the key-bars and held in said moved position by the locking mechanism referred to. With the construction illustrated in Figs. 1-9 inclusive, each key-bar is moved to its uppermost position by its returning spring 21 when the downward actuating pressure on said key-bar is released and the cores 35 remain in the position to which they have been moved by the operation of said key-bar without any tendency to move from that position.

As shown in Fig. 10, the device consists of a mounting plate 10b supporting horizontal plates 11a and 12a to hold key-bars 13a in vertical position for sliding movement through said horizontal plates. Each of the key-bars supports a rod 16a for turning movement in a flange member 18a formed from said key-bar, a stop washer 18b being carried by said rod below the flange member 18a to prevent longitudinal movement of the rod 16a through said flange member. The lower end of the rod 16a is threaded and extends through threaded openings in a U-shaped member 55 supported for vertical sliding movement on and relatively to the key-bar 13a. The member 55 is secured to an operating member 56 mounted on the opposite side of the key-bar 13a for movement relatively to the key-bar with the member 55, the connection being effected by a rivet 57 or the equivalent, extending through a longitudinal slot 58 in the key-bar 13a, as more clearly shown in Figs. 12 and 13. As shown in Figs. 12 and 13, the member 56 has formed from the lower end thereof a tongue 58a extending into the slot 58 to prevent turning movement of the member 56 on the key-bar 13a, and said member 56 is also provided with a lug 56b to engage the transverse bar 29 illustrated in Fig. 10, when the key-bar 13a is depressed. The U-shaped member 55 illustrated in Figs. 10 and 12 is preferably so made that its normal position is as indicated in dotted lines in Fig. 12 from which position it is sprung to the position indicated in full lines and threaded in that position to fit the threads on the rod 16a. To insert the threads on the rod 16a into the threaded openings in the member 55, said member is sprung to its position shown in full lines, and after the threaded portion of the rod has been extended through both of the threaded openings in the member 55, the pressure on the member is released and the spring tension of the member exerts sufficient pressure on the threads

to restrain the rod 16a from accidental turning movement. The transverse bars 29, 30 and 31, the shafts 25 and 26, the cranks 27 and 28 and the manner of supporting the transverse bars from the shafts by said cranks, are the same as illustrated in Fig. 1 and above described, the key-bars 13a extending vertically between the transverse bars 29 and 30, said shafts 25 and 26 being supported by the mounting plate 10b and a bearing plate 24a. In the construction shown in Figs. 10 and 11, the sole purpose of the bars 30 and 31 is to maintain corresponding angular rotation of the cranks 27 and 28.

As shown in Figs. 11 and 14, the shaft 25 has rigidly secured thereto a finger knob 54 for manually operating the cores 35, said cores, the coils 34 and their manner of support, and the operating mechanism provided to operate said cores by turning movement of the shaft 25, being the same as above described in connection with Fig. 2, the only difference being that in Fig. 11 I illustrate the adaptation of my improved mechanism to operate three cores 35 respectively associated with three inductance coils 34, as illustrated in Fig. 11, instead of using but two of said coils and associated cores as illustrated in Fig. 2. It will be understood that with either form of operating mechanism, any desired number of inductors may be used within the practical limits of the device. With the construction of Figs. 10-14, inclusive, the shaft 25 carries a returning spring 59 which engages the bearing plate 24a and the knob 54, and serves to hold the cores 35 in their innermost position in the coils 34 unless they are moved to some other position by the operating mechanism illustrated in Fig. 10, and held in their operated position.

As shown in Fig. 11, each of the key-bars 13a is provided at its lower end portion with a recess 13b to receive the lower edge of a swinging latch bar 60 pivotally supported at the ends of its opposite edge at 61 by bearing members 62 supported by the side walls carried by the mounting plate 10b. A spring 63 is provided to press the lower edge of the latch bar 60 against the edges of the key-bars 13a and to hold said latch bar in the recesses 13b when all of said key-bars are in their uppermost position, to which they are moved by returning springs 64 unless held in operated position by said latch bar. Each of the key-bars 13a is provided with an edge notch 13c above the recess 13b and spaced from said recess by an amount representing the stroke of the key-bar 13a. As a result of this construction, when a selected one of the key-bars 13a is depressed, the lower edge of the latch bar 60 is moved away from its locking position, which serves to release any key-bar on key-bars that may have previously been actuated, the lug 56b engages and operates the transverse bar 29 and thereby similarly operates the cores 35, which operation continues until the notch 13c is in line with the lower edge of the latch bar 60 for which position of the key-bar the latch bar enters the notch 13c under the action of the spring 63, and holds the key-bar in its depressed position, thus holding the cores 35 in their operated position, against the action of the returning spring 59. The amount of operation thereby imparted to the cores 35 is determined by the position of the operating member 56 on the key-bar 13a, the construction above described permitting said operating member 56 to have any desired position on said key-bar, within the range of movement possible with the throw of the key-

bars permitted by the location of the locking notches 13c.

The construction illustrated in Figs. 10-14, inclusive, has the advantage of taking up lost motion in the various operating connections involved and it has the further advantage of indicating the selection that has been effected by the operation of the key-bars. On the other hand, the construction illustrated in Figs. 1-9, inclusive, has the advantage of positively moving the cores 35 in either direction, instead of relying on a spring to move them in one direction, as is the case with the construction illustrated in Figs. 10-14, inclusive. A further advantage of the construction illustrated in Figs. 1-9, inclusive, is that less operating pressure is required on the push buttons than with the other construction, inasmuch as it is not necessary to overcome the pressure of a core returning spring, in addition to the friction of the parts and the pressures of the key-bar returning springs.

In Figs. 15 and 16 I illustrate a construction of sector 14c which may be employed with the operating mechanism illustrated in Figs. 1-9, inclusive, in which the sector consists of sheet metal having integral lugs 14d and 14e formed by suitable tools from parts of the sheet metal from which the body portion of the sector is formed.

By my invention I have therefore provided effective means for transforming the reciprocating movement of a selective push-button mechanism into rotary movement, and then again transformed said rotary movement into reciprocating movement to operate the longitudinally movable cores of variable inductance devices, and at the same time multiplying the movement imparted to said cores, most of the parts of which mechanism may be cheaply produced by stamping operations, since the parts for any one of said selective devices are duplicates of parts of the rest of said selective devices.

While I have shown my invention in the particular embodiment above described, it will be understood that I do not limit myself thereto as I may employ equivalents thereof without departing from the scope of the appended claims.

Having thus described my invention what I claim is:

1. In a selective operating mechanism for a variable inductance device of the class wherein the inductance device includes a coil and a ferromagnetic core movable longitudinally relatively to said coil to selectively adjust the inductance of the device to any desired one of a plurality of different amounts to tune a resonant radio circuit to a desired one of a range of frequencies, the combination of a mounting plate for supporting the inductance device on one side of said plate in a first plane parallel with said plate and with the core movable substantially parallel with said plate, a plurality of selective operating key-devices mounted on the other side of said plate in a second plane parallel with said plate for rectilinear movement substantially parallel therewith, and transfer mechanism including a shaft extending through said plate and adapted for operating connection with said coil, said transfer mechanism having operative relation with said operating key-devices imparting to said shaft different amounts of angular movement determined respectively by said operating key-devices, said transfer mechanism including a bar connected with said shaft and mounted thereon for transverse angular and parallel movement to operate said shaft, said

bar extending across the paths of movement of and adjacent to said key-devices for operation by any selected one of said key-devices.

2. In a selective operating mechanism for a variable inductance device of the class wherein the inductance device includes a coil and a ferromagnetic core movable longitudinally relatively to said coil to selectively adjust the inductance of the device to any desired one of a plurality of different amounts to tune a resonant radio circuit to a desired one of a range of frequencies, the combination of a mounting plate for supporting the inductance device on one side of said plate in a first plane parallel with said plate and with the core movable substantially parallel with said plate, a plurality of selective operating key-devices mounted on the other side of said plate in a first plane parallel with said plate for rectilinear movement substantially parallel therewith, and transfer mechanism including a shaft extending through said plate and adapted for operating connection with said coil, said transfer mechanism having operative relation with said operating key-devices imparting to said shaft different amounts of angular movement determined respectively by said operating key-devices, each of said operating key-devices including a first and longitudinally reciprocable bar, and a member carried by said first bar and movable thereon to different positions of adjustment effecting different amounts of angular movement of said shaft for a given amount of movement of said first bar, said transfer mechanism including a second bar connected with said shaft and mounted thereon for transverse angular and parallel movement to operate said shaft, said second bar extending across the paths and in the range of movement of the adjustable members on the bars of said key-devices for operation by said key-devices an amount determined in any case by the adjustment of the operating adjustable member.

3. In a selective operating mechanism for a variable inductance device of the class wherein the inductance device includes a coil and a ferromagnetic core movable longitudinally relatively to said coil to selectively adjust the inductance of the device to any desired one of a plurality of different amounts to tune a resonant radio circuit to a desired one of a range of frequencies, the combination of a mounting plate for supporting the inductance device on one side of said plate in a first plane parallel with said plate and with the core movable substantially parallel with said plate, a plurality of selective operating key-devices mounted on the other side of said plate in a second plane parallel with said plate for rectilinear movement substantially parallel therewith, and transfer mechanism including a shaft extending through said plate and adapted for operating connection with said coil, said transfer mechanism having operative relation with said operating key-devices imparting to said shaft different amounts of angular movement determined respectively by said operating key-devices, each of said operating key-devices including a first and longitudinally reciprocable bar, and a member carried by said first bar and movable thereon to different positions of adjustment effecting different amounts of angular movement of said shaft for a given amount of movement of said first bar, said transfer mechanism including second and third bars each connected with said shaft and mounted thereon for transverse angular and parallel movement to op-

erate said shaft, each of said second and third bars extending across the paths and in the range of movement of the adjustable members on the bars of said key-devices for operation by said key-devices an amount determined in any case by the adjustment of the operating adjustable member, said second and third bars being mounted and connected for movement in opposite directions, whereby the one of said second and third bars first engaged in any case by an operating adjustable member depending upon the initial position of said shaft, becomes the operated bar, and the other of said second and third bars becomes a stop bar stopping further movement of the operating adjustable member by engagement therewith.

4. In a selective operating mechanism for a variable inductance device of the class wherein the inductance device includes a coil and a ferromagnetic core movable longitudinally relatively to said coil to selectively adjust the inductance of the device to any desired one of a plurality of different amounts to tune a resonant radio circuit to a desired one of a range of frequencies, the combination of a mounting plate for supporting the inductance device on one side of said plate in a first plane parallel with said plate and with the core movable substantially parallel with said plate, a plurality of selective operating key-devices mounted on the other side of said plate in a second plane parallel with said plate for rectilinear movement substantially parallel therewith, and transfer mechanism including a shaft extending through said plate and adapted for operating connection with said core, said transfer mechanism having operative relation with said operating key-devices imparting to said shaft different amounts of angular movement determined respectively by said operating key-devices, each of said operating key-devices including a first and longitudinally reciprocable bar, a sector pivotally carried by each of said first bars and movable angularly thereon to different positions of adjustment effecting different amounts of angular movement of said shaft for a given amount of movement of said first bar, and clamping means for holding said sector in adjusted position on said bar carrying said sector, said transfer mechanism including a second bar connected with said shaft and mounted thereon for transverse angular and parallel movement to operate said shaft, said second bar extending across the paths and in the range of movement of the sectors on the bars of said key-devices for operation by said key-devices an amount determined in any case by the adjustment of the operating sector, each of said sectors including a lug projecting perpendicularly therefrom for engaging and operating said second bar.

5. In a selective operating mechanism for a variable inductance device of the class wherein the inductance device includes a coil and a ferromagnetic core movable longitudinally relatively to said coil to selectively adjust the inductance of the device to any desired one of a plurality of different amounts to tune a resonant radio circuit to a desired one of a range of frequencies, the combination of a mounting plate for supporting the inductance device on one side of said plate in a first plane parallel with said plate and with the core movable substantially parallel with said plate, a plurality of selective operating key-devices mounted on the other side of said plate in a second plane parallel with said plate for rectilinear movement substantially parallel there-

with, and transfer mechanism including a shaft extending through said plate and adapted for operating connection with said core, said transfer mechanism having operative relation with said operating key-devices imparting to said shaft different amounts of angular movement determined respectively by said operating key-devices, each of said operating key-devices including a first and longitudinally reciprocable bar, a sector pivotally carried by each of said first bars and movable angularly thereon to different positions of adjustment effecting different amounts of angular movement of said shaft for a given amount of movement of said first bar, and clamping means for holding said sector in adjusted position on said bar carrying said sector, said transfer mechanism including second and third bars each connected with said shaft and mounted thereon for transverse angular and parallel movement to operate said shaft, each of said second and third bars extending across the paths and in the range of movement of the sectors on the bars of said key-devices for operation by said key-devices of an amount determined in any case by the adjustment of the operating sector, said second and third bars being mounted and connected for movement in opposite directions, whereby the one of said second and third bars first engaged in any case by an operating sector depending upon the initial position of said shaft, becomes the operated bar, and the other of said second and third bars becomes a stop bar stopping further movement of the operating sector by engagement therewith, each of said sectors including two lugs oppositely disposed and projecting oppositely and perpendicularly from the sector for operating and stop engagement with said second and third bars.

6. In a selective operating mechanism for a variable inductance device including two elements one of which is movable relatively to the other, the combination of two parallel shafts, angularly aligned cranks of the same effective radius secured to said shafts, a bar articulating with and connecting said cranks, the center-to-center distance of said bar connections being equal to the center-to-center distance between said shafts, selective key bars in alignment with and directed transversely of said bar for moving said bar different amounts laterally, and operating connections between one of said shafts and the movable element of said inductance device.

7. In a selective operating device for variable inductance mechanism including a coil and a ferromagnetic core movable longitudinally relatively to said coil for radio tuning purposes, the combination of a plurality of selective operating key-devices mounted for rectilinear and substantially parallel movement, and transfer mechanism including a rotary shaft for operating connection with the movable element of said inductance mechanism, said transfer mechanism having operative relation with said operating key-devices imparting to said shaft different amounts of angular movement determined respectively by said operating key-devices, said transfer mechanism including a bar connected with said shaft and mounted thereon for transverse angular and parallel movement to operate said shaft, said bar extending across the paths of movement of and adjacent to said key-devices for operation by any selected one of said key-devices.

8. In a selective operating device for variable inductance mechanism including a coil and a

ferromagnetic core movable longitudinally relatively to said coil for radio tuning purposes, the combination of a plurality of selective operating key-devices mounted for rectilinear and substantially parallel movement, and transfer mechanism including a rotary shaft for operating connection with the movable element of said inductance mechanism, said transfer mechanism having operative relation with said operating key-devices imparting to said shaft different amounts of angular movement determined respectively by said operating key-devices, each of said operating key-devices including a first and longitudinally reciprocable bar, and a member carried by said first bar and movable thereon to different positions of adjustment effecting different amounts of angular movement of said shaft for a given amount of movement of said first bar, said transfer mechanism including a second bar connected with said shaft and mounted thereon for transverse angular and parallel movement to operate said shaft, said second bar extending across the paths and in the range of movement of the adjustable members on the bars of said key-devices for operation by said key-devices an amount determined in any case by the adjustment of the operating adjustable member.

9. In a selective operating device for variable inductance mechanism including a coil and a ferromagnetic core movable longitudinally relatively to said coil for radio tuning purposes, the combination of a plurality of selective operating key-devices mounted for rectilinear and substantially parallel movement, and transfer mechanism including a rotary shaft for operating connection with the movable element of said inductance mechanism, said transfer mechanism having operative relation with said operating key-devices imparting to said shaft different amounts of angular movement determined respectively by said operating key-devices, said transfer mechanism including first and second bars each connected with said shaft and mounted thereon for transverse angular and parallel movement to operate said shaft, each of said first and second bars extending across the paths of movement of said key-devices for operation by any selected one of said key-devices, said first and second bars being mounted and connected for movement in opposite directions, whereby the one of said first and second bars first engaged in any case by any selected one of said key-devices depending upon the initial position of said shaft, becomes the operated bar, and the other of said first and second bars becomes a stop bar stopping further movement of the selected key-bar by engagement therewith.

10. In a selective operating device for variable inductance mechanism including a coil and a ferromagnetic core movable longitudinally relatively to said coil for radio tuning purposes, the combination of a plurality of selective operating key-devices mounted for rectilinear and substantially parallel movement, and transfer mechanism including a rotary shaft for operating connection with the movable element of said inductance mechanism, said transfer mechanism having operative relation with said operating key-devices imparting to said shaft different amounts of angular movement determined respectively by said operating key-devices, each of said operating key-devices including a first and longitudinally reciprocable bar, and a member carried by said first bar and movable thereon to different positions of

adjustment effecting different amounts of angular movement of said shaft for a given amount of movement of said first bar, said transfer mechanism including second and third bars each connected with said shaft and mounted thereon for transverse angular and parallel movement to operate said shaft, each of said second and third bars extending across the paths and in the range of movement of the adjustable members on the bars of said key-devices for operation by said key-devices an amount determined in any case by the adjustment of the operating adjustable member, said second and third bars being mounted and connected for movement in opposite directions, whereby the one of said second and third bars first engaged in any case by an operating adjustable member depending upon the initial position of said shaft, becomes the operated bar, and the other of said second and third bars becomes a stop bar stopping further movement of the operating adjustable member by engagement therewith.

11. In a selective operating device for variable inductance mechanism including a coil and a ferromagnetic core movable longitudinally relatively to said coil for radio tuning purposes, the combination of a plurality of selective operating key-devices mounted for rectilinear and substantially parallel movement, and transfer mechanism including a rotary shaft for operating connection with the movable element of said inductance mechanism, said transfer mechanism having operative relation with said operating key-devices imparting to said shaft different amounts of angular movement determined respectively by said operating key-devices, each of said operating key-devices including a first and longitudinally reciprocable bar, a sector pivotally carried by each of said first bars and movable angularly thereon to different positions of adjustment effecting different amounts of angular movement of said shaft for a given amount of movement of said first bar, and clamping means for holding said sector in adjusted position on said bar carrying said sector, said transfer mechanism including a second bar connected with said shaft and mounted thereon for transverse angular and parallel movement to operate said shaft, said second bar extending across the paths and in the range of movement of the sectors on the bars of said key-devices for operation by said key-devices an amount determined in any case by the adjustment of the operating sector, each of said sectors including a lug projecting perpendicularly therefrom for engaging and operating said second bar.

12. In a selective operating device for variable inductance mechanism including a coil and a ferromagnetic core movable longitudinally relatively to said coil for radio tuning purposes, the combination of a plurality of selective operating key-devices mounted for rectilinear and substantially parallel movement, and transfer mechanism including a rotary shaft for operating connection with the movable element of said inductance mechanism, said transfer mechanism having operative relation with said operating key-devices imparting to said shaft different amounts of angular movement determined respectively by said operating key-devices, each of said operating key-devices including a first and longitudinally reciprocable bar, a sector pivotally carried by each of said first bars and movable angularly thereon to different positions of

adjustment effecting different amounts of angular movement of said shaft for a given amount of movement of said first bar, and clamping means for holding said sector in adjusted position on said bar carrying said sector, said transfer mechanism including second and third bars each connected with said shaft and mounted thereon for transverse angular and parallel movement to operate said shaft, each of said second and third bars extending across the paths and in the range of movement of the sectors on the bars of said key-devices for operation by said key-devices of an amount determined in any case by the adjustment of the operating sector, said second and third bars being mounted and connected for movement in opposite directions, whereby the one of said second and third bars first engaged in any case by an operating sector depending upon the initial position of said shaft, becomes the operated bar, and the other of said second and third bars becomes a stop bar stopping further movement of the operating sector by engagement therewith, each of said sectors including two lugs oppositely disposed and projecting oppositely and perpendicularly from the sector for operating and stop engagement with said second and third bars.

13. In a selective operating mechanism for a variable inductance device including two elements one of which is movable relatively to the other, the combination of two parallel shafts, a first pair of angularly aligned cranks secured respectively to said shafts, a second pair of angularly aligned cranks secured respectively to said shafts and displaced angularly from the cranks of said first pair, the cranks of each pair having the same effective radius, a first bar articulating with and connecting the first pair of cranks, a second bar articulating with and connecting the second pair of cranks, the center-to-center distance of the crank connections of each of said bars being equal to the center-to-center distance between said shafts, selective key-bars in alignment with and directed transversely of said first and second bars for moving said first and second bars laterally and thereby imparting different amounts of angular movement to each of said shafts, and operating connections between one of said shafts and the movable element of said inductance device, said first and second bars being mounted for simultaneous movement in opposite directions, whereby said first and second bars are interchangeably an operated bar and a stop bar for said key-bars depending upon the positions of said first and second bars at the beginning of the operation of any selected one of said key-bars.

14. A radio tuner including in combination, frame means including a front portion and a back portion, a plurality of control units, with each of said control units including linearly movable control means on said frame means and available for operation at the front portion thereof, additional control means supported on said frame means at the back portion thereof and movable in a linear direction, and motion-transferring means intermediate said two linearly moving means and operatively associating the same including means for converting linear movement into rotary movement in the motion-transferring means and then converting the rotary movement into linear movement in the additional linearly movable control means, said control units including selectively operable key bars having respectively operating sectors piv-

otally mounted thereon and determining the amounts of operating movement of said key bars.

15. A radio tuner including in combination, frame means including a front portion and a back portion, a plurality of control units, with each of said control units including linearly movable control means on said frame means and available for operation at the front portion thereof, additional control means supported on said frame means at the back portion thereof and movable in a linear direction, and motion-transferring means intermediate said two linearly moving means and operatively associating the same including means for converting linear movement into rotary movement in the motion-transferring means and then converting the rotary movement into linear movement in the additional linearly movable control means, said control units including selectively operable key bars each carrying means changing as desired its amount of operating movement.

16. A radio tuner including in combination, frame means including a front portion and a back portion, a plurality of control units, with each of said control units including linearly movable control means on said frame means and available for operation at the front portion thereof, additional control means supported on said frame means at the back portion thereof and movable in a linear direction, and motion-transferring means intermediate said two linearly moving means and operatively associating the same including means for converting linear movement into rotary movement in the motion-transferring means and then converting the rotary movement into linear movement in the additional linearly movable control means, said control units including selectively operable key bars each having a member movable thereon changing as desired its amount of operating movement.

17. A radio tuner including in combination, frame means including a front portion and a back portion, a plurality of control units, with each of said control units including linearly movable control means on said frame means and available for operation at the front portion thereof, additional control means supported on said frame means at the back portion thereof and movable in a linear direction, and motion-transferring means intermediate said two linearly moving means and operatively associating the same including means for converting linear movement into rotary movement in the motion-transferring means and then converting the rotary movement into linear movement in the additional linearly movable control means, said motion-transferring means including a laterally movable bar for operating actuation in common by said control units.

18. A radio tuner including in combination, frame means including a front portion and a back portion, a plurality of control units, with each of said control units including linearly movable control means on said frame means and available for operation at the front portion thereof, additional control means supported on said frame means at the back portion thereof and movable in a linear direction, and motion-transferring means intermediate said two linearly moving means and operatively associating the same including means for converting linear movement into rotary movement in the motion-transferring means and then converting the rotary movement into linear movement in the motion-transferring means and then converting the rotary movement into linear movement in the

additional linearly movable control means, said motion-transferring means including a first and laterally movable bar for operating actuation in common by said control units and including also a second bar laterally movable by and oppositely to said first bar for in common stopping movement of said control units.

19. A radio tuner including in combination, frame means including a front portion and a back portion, a plurality of control units, with each of said control units including linearly movable control means on said frame means and available for operation at the front portion thereof, additional control means supported on said frame means at the back portion thereof and movable in a linear direction, and motion-transferring means intermediate said two linearly moving means and operatively associating the same including means for converting linear movement into rotary movement in the motion-transferring means and then converting the rotary movement into linear movement in the additional linearly movable control means, said control units including selectively operable key bars each carrying means changing as desired its amount of operating movement, said motion-transferring means including a bar extending across the paths of movement of said key bars for lateral operating movement by a selected one of said key bars.

20. A radio tuner including in combination, frame means including a front portion and a back portion, a plurality of control units, with each of said control units including linearly movable control means on said frame means and available for operation at the front portion thereof, additional control means supported on said frame means at the back portion thereof and movable in a linear direction, and motion-

- transferring means intermediate said two linearly moving means and operatively associating the same including means for converting linear movement into rotary movement in the motion-transferring means and then converting the rotary movement into linear movement in the additional linearly movable control means, said control units including selectively operable key bars each having a member movable thereon 5 changing as desired its amount of operating movement, said motion-transferring means including a first bar extending across the paths of movement of said key bars for lateral operating movement by a selected one of said key bars, and 10 15 including also a second bar extending across the paths of movement of said key bars and laterally movable by and oppositely to said first bar for stopping movement of a selected key bar.
21. A radio tuner including in combination, frame means including a front portion and a back portion, a plurality of control units, with each of said control units including linearly movable first control means on said frame means and available for operation at the front portion thereof, additional control means supported on said frame means at the back portion thereof and movable in a linear direction, motion-transferring means intermediate said two linearly moving means and operatively associating 25 30 the same including means for converting linear movement into rotary movement in the motion-transferring means and then converting the rotary movement into linear movement in the additional linearly movable control means, and devices returning said first control means to its original condition after each operation and leaving said additional control means in its operated condition.

MARTIN J. KIRK.

CERTIFICATE OF CORRECTION.

Patent No. 2,344,091.

March 14, 1944.

MARTIN J. KIRK.

It is hereby certified that error appears in the printed specification of the above numbered patent requiring correction as follows: Page 1, first column, line 36, for "employed" read --employed--; line 37, after "proportions" insert a comma; page 5, second column, line 14, claim 2, for "plate in a" read --plate in a--; line 18, same claim, for "first" read --second--; and that the said Letters Patent should be read with this correction therein that the same may conform to the record of the case in the Patent Office.

Signed and sealed this 16th day of May, A. D. 1944.

Leslie Frazer
